[57] CLAIM

The ornamental design for a beverage dispenser, substantially as shown and described.

DESCRIPTION

FIG. 1 is a front elevational view of a beverage dispenser embodying our new design.

FIG. 2 is a top plan view thereof.

FIG. 3 is a side elevational view thereof as seen from the left side of FIG. 1; the side opposite being a mirror image thereof.

FIG. 4 is a horizontal sectional view taken along line 4—4 of FIG. 3.

FIG. 5 is a rear elevational view thereof.

FIG. 6 is a horizontal sectional view taken along line 6—6 of FIG. 5.
